MOTOR VEHICLE CRASH GUARD

Leonard H. Sobel, 452 Beach 138th St.,
Rockaway Park, N.Y. 11694

Filed May 22, 1969, Ser. No. 17,279

Term of patent 14 years

Int. Cl. D12—14

U.S. Cl. D14—6

FIG. 1

FIG. 2

FIG. 3

FIG. 4

FIG. 5

FIG. 6

FIG. 7

FIG. 8

FIG. 9

FIG. 10

FIG. 1 is a side view of a motor vehicle crash guard, showing my new design;

FIG. 2 is a front view thereof;

FIG. 3 is a rear view thereof;

FIG. 4 is a top view thereof;

FIG. 5 is a bottom view thereof;

FIG. 6 is a side view showing my new design in a modified form;

FIG. 7 is a front view thereof;

FIG. 8 is a rear view thereof;

FIG. 9 is a top view thereof; and

FIG. 10 is a bottom view thereof.

The bumpers which are shown in broken lines are included for illustrative purposes only.

I claim:

The ornamental design for a motor vehicle crash guard, as shown and described.
